UNITED STATES PATENT OFFICE.

THOMAS E. TAYLOR, OF MANSFIELD, OHIO, ASSIGNOR TO THE TAPPAN STOVE COMPANY, OF MANSFIELD, OHIO, A CORPORATION OF OHIO.

STOVE STRUCTURE.

Application filed May 26, 1924. Serial No. 715,859.

To all whom it may concern:

Be it known that I, THOMAS E. TAYLOR, a citizen of the United States, residing at Mansfield, in the county of Richland and State of Ohio, have invented certain new and useful Improvements in Stove Structures, of which the following is a specification.

My invention relates to improvements in stove structures, and more particularly to improvements in oven fronts for ranges and the like, same embodying an improved oven front or main front frame, together with improved means for connecting the latter to the oven walls through the medium of fastening elements which are internally arranged and covered by the front frame and stove walls, thereby providing what may be termed a "boltless front", there being no bolts or crevices exposed to catch dirt, thus rendering the same of neater appearance and facilitating cleaning.

The primary object of the invention is to provide a generally improved stove or oven front structure of the type or class indicated, which will be exceedingly simple in construction, cheap of manufacture, and efficient in use.

A further and important object is the provision of an improved oven front or main front frame having improved interiorly arranged fastening elements and clamps for connecting the oven walls to the front frame whereby the latter may be readily attached to or detached from the oven walls.

With the above mentioned and other ends in view, the invention consists in the novel construction, arrangement and combination of parts, hereinafter described, illustrated in one of its embodiments in the accompanying drawings, and particularly pointed out in the appended claims.

Referring to the drawings, forming a part of this specification, Figure 1 is a perspective view of the oven portion of a stove of the range type, constructed in accordance with this invention.

Fig. 2, an enlarged front elevation of one of the upper corner portions of the oven front frame, the door being removed therefrom and illustrating the single screw or fastening element for securing the improved internally arranged corner clamp whereby the

oven front frame and oven walls may be secured together. 55

Fig. 3, an enlarged vertical transverse sectional view, partly in rear elevation, of the upper portion of the oven front frame and its connections, one of the inner corner clamps being removed for the purpose of 60 clearer illustration of the parts.

Fig. 4, a transverse horizontal sectional view, taken on line 4-4 of Fig. 3.

Fig. 5, a plan view of the rear or under-side of one of the corner clamps, detached; 65 Fig. 6, a fragmentary perspective view of a wall connecting seaming strip, detached.

Similar numerals of reference designate like parts throughout all the figures of 70 the drawings.

The improved oven front or door frame may be of any suitable and convenient construction and so likewise the general form and arrangement of the oven side and top walls. In the present instance, and for the 75 purpose of illustration, I have shown my improvements incorporated in an oven front frame and oven of the general type disclosed and claimed in my Patent No. 1481633, issued January 22nd, 1924. 80

As in that patent the oven door or main frame is of cast metal and comprises a main door section 1, and extension door sections 2.

The main section 1 is preferably of rectangular form, as shown, and comprises the under channelled side members 1 and cross members 1^a. The members 1 and 1^a of the main door section or frame are preferably provided about their inner marginal edges with an inset marginal edge or flange a, 90 to receive and form a seat for the marginal edges of the main or baking oven door 3 when the latter is closed, as shown in Fig. 1 of the drawings.

The lower or extension frame sections 2, are adapted to form the sides of the lower or broiler door opening and to receive the marginal edges of the lower or broiler door 4.

As a means of permitting some relative movement between the broiler door extension members 2 and the main section 3 to prevent breakage in shipping or moving, as well as facilitating repair of the parts, the upper ends of the members 2 are jointed to 105 the lower ends of the main section 3 through

the medium of fastening elements or screws 4^a, the joints being otherwise as disclosed and claimed in my said patent, and forming no specific part of the present invention 6 need not be described in detail.

The lower ends of the lower or extension frame section 2, forming the sides of the broiler door opening are secured to the horizontal base band 5, of the stove frame by 10 means of attaching elements or bolts 6.

As a means of connecting the oven front frame to the oven walls through the medium of internally arranged and covered fastening elements, and particularly as a means 15 of securely binding the oven top and sides to the front frame and giving a much broader clamping surface than ordinary fastening elements, such as bolts and screws would afford when connected in the ordinary manner, the oven front section 1 is provided at its corners with rearwardly extending projections or lugs 1^b, (see Figs. 3 and 4) and the oven top and side walls 7, are provided with flanges 7^a, extending behind and covered by the front frame, said flanges 7^a being provided with openings 7^b, registering with and receiving the projections or lugs 1^b of the front frame.

As a means of clamping the front portions of the oven walls to the front frame and further reinforcing the parts, corner clamp members 8, are provided, said corner clamps 8 being provided with openings 8^a, receiving the lugs or projections 1^b, and being also preferably provided on their under sides with friction or clamping lugs 8^b, (see Fig. 5) for engaging with the flanges 7^a of the oven walls, and the inner flanges of the oven frame 1.

As a means of detachably connecting and adjusting the clamps 8 by means operable from the exterior of the frame when the oven door 3 is open or removed, screw bolts 8^c extend through openings in the corner portions of the inset flange α of the oven front frame and through openings 8^a, (see Fig. 5) of the corner clamps being secured by means of nuts 8^e. The heads of the fastening elements 8^c are countersunk in the inset corner portions α of the front frame and over which the corner portions of the oven door 3 close and it will be apparent that when the door is open the fastening elements 8^c may be drawn up or loosened without the necessity of removing the oven linings or disturbing the interior parts. The inner peripheries of the vertical members of the front frame are preferably provided with rearwardly extending lugs 1^d adapted to extend over and engage with the front edges of the oven lining walls 9, as shown most clearly in Figs. 3 and 4 of the drawings.

As a convenient means of coupling or connecting the top and side walls 7 of the oven 65 and securing the splasher wall 10 along its

upper edges without the use of fastening elements such as screws or bolts, a wall coupling or seaming strip is provided; said coupling strip comprising oppositely extending loops or crimps 11, forming oppositely opening wall-receiving recesses receiving the adjacent edges 7^c of the adjacent walls, the second or intermediate crimp 11 terminating in a depending clamping flange 11^a, receiving and clamping the upper marginal edge of the splasher wall 10, as shown most clearly in Fig. 3 of the drawings. The rear edge of the splasher 10 and the adjacent edge of the rear splasher 10^a may be conveniently covered and held by means of a 80 vertically extending strip 12, as shown most clearly in Fig. 1 of the drawings.

Having thus described one of the embodiments of my invention, without having attempted to set forth all the forms in which it may be made, or all the modes of its use, what I claim and desire to secure by Letters Patent is,—

1. In a stove structure, the combination with a front frame and an oven structure 90 extending therefrom, frame and oven connecting clamp members at the rear of said front frame, and concealed externally operable means for securing and adjusting said clamp members.

2. In a stove oven structure, the combination with an oven front frame and oven walls having flanges turned in behind said oven front frame, clamp members at the rear of said oven front frame, and concealed means for securing and adjusting said clamps to said flanges and oven front frame from the exterior of the latter.

3. In a stove structure, an oven front frame provided with corner lugs on its inner side, stove walls having marginal edges covered by said frame and having openings receiving said lugs, corner clamps provided with openings receiving said lugs, and means operable from the exterior of said frame for connecting and adjusting said clamps.

4. In an oven structure for ranges, the combination with an oven front frame provided at its corners with rearwardly extending projections, and an oven structure having openings engaged by said projections; of corner clamps provided with openings receiving said projections and engaging said oven structure, and adjustable clamp connecting elements.

5. In a stove structure, an oven front frame provided with lugs on its inner side, stove walls provided with inwardly extending flanges covered by said frame and provided with openings receiving said lugs, and clamp members adjustably connected to said front frame and extending on the inner sides of said flanges and provided with openings receiving said lugs.

6. In an oven structure, the combination with an oven front frame, an oven structure and clamps detachably connected to said oven structure and provided with fastening elements internally arranged on said front frame, said oven front frame being provided with lugs and said oven structure being provided with openings receiving said lugs.
- 10 7. In a stove, the combination with an oven front frame provided at its corners with rearwardly extending projections, and oven walls provided with inwardly extending marginal flanges having openings engaged by said projections; of corner clamps connected to said frame and provided with openings receiving said projections and engaging said marginal flanges between said frame and clamp members.
- 20 8. In a stove structure, the combination with an oven front frame, oven walls having flanges covered by said oven front frame, and clamps engaging said flanges provided with openings and fastening elements internally arranged and secured to said front frame, said oven front frame being provided with lugs extending through said clamp openings, and said oven wall flanges being provided with openings slidably receiving said lugs.
- 25 9. In a stove structure, the combination with stove wall and splasher members hav-
- ing their edges adjacent; of a coupling strip having reversely arranged U-shaped folds curled about said adjacent edges of said walls.
10. In a stove structure, the combination with adjacent sheet metal walls; of a coupling and seaming strip embodying oppositely extending loops receiving the edges of said walls and terminating in a clamping flange extending over the marginal edges of an adjacent splasher wall.
11. In a range structure, a pair of adjacent oven walls, a coupling strip embodying loops interposed between and receiving the adjacent edges of said walls and terminating in a depending clamping flange, and a splasher wall having its marginal edges received and held by said depending clamping flange of said strip.
12. In a range structure including oven top and side walls having adjacent edges running horizontally at one side of the cooking top, a strip having longitudinally crimped U-shaped folds interposed between and receiving said adjacent wall edges and terminating in an exterior depending clamping flange, and a splasher wall at one side of said cooking top having its upper edge engaged by said clamping flange.

In testimony whereof I have affixed my signature.

THOMAS E. TAYLOR.
